SEWING MACHINE

Henry C. Nissen, Stratford, Conn., assignor to
The Singer Manufacturing Company, Elizabeth, N. J., a corporation of New Jersey

Application April 27, 1935, Serial No. 18,519

5 Claims. (Cl. 112—127)

This invention relates to improvements in edge-guiding devices for use in connection with trimmer mechanisms for sewing machines, and more particularly with underedge trimmers of the horizontally vibratory or so-called Barber type.

It is the primary object of the present invention to provide means for conveniently handling the work during stitching operations requiring the employment of a trimmer mechanism and an edge-guide, either separately or in combination.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a view, partly in front elevation and partly in section, of a portion of a sewing machine containing a preferred embodiment of the invention. Fig. 2 represents a vertical section, substantially on the line 2—2 of Fig. 1, illustrating the trimmer actuating mechanism. Fig. 3 represents a vertical section, substantially on the line 3—3 of Fig. 1, illustrating the trimmer and edge-guide coupling device. Fig. 4 is a top plan view of a portion of the sewing machine cloth-plate, illustrating both the trimmer-knife and the edge-guide in full lines in their operative position, and in dotted lines in their inoperative position. Fig. 5 is a top plan view similar to Fig. 4, but with the trimmer-knife in its operative position and the edge-guide swung into its inoperative position.

As illustrated in the drawings, the sewing machine has a bed-plate 1 upon which is suitably secured a throat-plate 2 provided with a feed-slot 3 and a needle-aperture 4. Adjacent to the needle-aperture 4, the throat-plate is recessed to provide an arcuate wall 5.

Operating through the throat-plate feed-slot 3 is a feed-dog 6 opposed by the usual presser-roller 7, the stitching being effected by a needle 8, carried by a vertically reciprocating needle-bar 9 and cooperating with a suitable loop-taker (not shown).

The trimmer mechanism illustrated in the drawings corresponds substantially with the disclosure in the U. S. patent to F. M. Card, No. 1,963,933, June 19, 1934. In general, this mechanism comprises a supporting plate 10, suitably

secured upon the bed-plate 1 and upon which a knife-driving lever 11 is pivotally secured by a screw 12 for horizontal swinging movements. Pivotally depending from the driving lever 11 and extending through a slot 13 in the bed-plate 1 is a yolk-member 14 providing a guideway for a slide-block 15. The slide-block 15 is pivotally secured by a screw 16 upon the upper end of a crank-arm 17 carried by a horizontally disposed rock-shaft 18 journaled in a bearing bracket 19 depending from the bed-plate 1. Suitably clamped upon the rock-shaft 18 is a forked arm 20 engaged by a cam 21 carried by the usual rotary loop-taker actuating shaft 22.

Pivotally secured by a screw 23 upon the driving lever 11, for swing-out movements about a vertical axis, is a knife-carrying lever 24 upon which the slotted shank of a trimmer knife 25 is adjustably secured in a suitable manner, said knife having the usual vertically depending fin 26 slidingly engaging the arcuate wall 5 of the throat-plate recess. The tail end of the knife-carrying lever 24 is adapted to resiliently engage an upwardly open notch 27 provided in an angular plate 28 adjustably secured by a screw 29 upon the knife-driving lever 11. When the knife-carrying lever 24 is seated in the notch 27, said lever 24 is anchored to the driving lever 11 for horizontal vibration therewith. However, by reason of the resilience of the tail of the knife-carrying lever 24, it may be readily lifted out of the notch 27, whereupon the lever 24 may be swung horizontally about its fulcrum-axis 23 to carry the knife 25 into an inoperative position, as illustrated by dotted lines in Fig. 4 of the drawings.

The improved edge-guiding device is mounted upon an angular supporting bracket having its base 30 secured by a screw 31 upon the trimmer-supporting plate 10 for adjustment crosswise of the line of seam formation. Rising from the bracket-base 30 is an upstanding wall 32 bent laterally to provide a horizontally disposed supporting member 33 overhanging the fulcrum-axes of the knife-driving and knife-carrying levers.

A two-armed lever 34, 35 is pivotally secured upon the bracket-member 33, by means of a pivot-bolt 36 which is preferably in vertical alignment with or closely adjacent to the fulcrum-axis of the knife-carrying lever 24. The arm 34 of said lever overhangs the trimmer-knife 25 and is bent downwardly into close proximity to said knife, the free end of said arm 34 serving as an edge-guide for the work.

Threaded into the arm 35 of the edge-guide lever is a bushing 37 having its head provided with a diametral groove 38. Vertically slidable in the bushing 37 is a shouldered plunger 39 from which laterally extends a pin 40 adapted to enter the groove 38 of the bushing. The reduced lower end 41 of the plunger is adapted to enter a slot 42 provided in the knife-lever 24, a spring 43 housed by the bushing 37 urging the plunger yieldingly downwardly. The knife-lever slot 42 and the plunger end 41 are so proportioned as to provide sufficient clearance permitting normal operation of the trimmer-knife to sever the work without actuation of the edge-guide. However, when the knife-lever 24 is disengaged from the driving lever 11, i. e., when the tail end of the lever is lifted out of the notch 27, and is shifted into an inoperative position as illustrated by dotted lines in Fig. 4 20 of the drawings, the edge-guide lever 34, 35 is also swung into an inoperative position by the coupling connection between the plunger 39, 41 and said knife-lever.

By slightly lifting the plunger 39, against the action of the spring 43, and turning said plunger about its longitudinal axis, so that the pin 40 is disposed transversely of the bushing groove 38, (Fig. 5) the plunger-end 41 is withdrawn from the knife-lever slot 42. The knife-lever and the edge-guide may now be swung into inoperative positions independently of each other, so that either the knife or the edge-guide may be employed separately or in combination, according to the nature of the work.

In order to provide for conveniently shifting the edge-guide lever 34, 35 into and out of operative position, said lever is preferably provided with an operating handle 44 and with a horizontally-disposed segmental arm 45 provided in a side edge thereof with spaced stop-notches 46 and 47. Secured by screws 48 upon the wall 32 of the edge-guide bracket is a spring 49 bent to provide a V-shaped detent 50 adapted to yieldingly enter the stop-notches 46, 47 in the arm 45, to definitely locate the operative and inoperative positions of the edge-guide and to normally hold the edge-guide in said positions.

Having thus set forth the nature of the invention, what I claim herein is:—

1. In a sewing machine, in combination, stitch-forming mechanism, trimmer mechanism including a work-severing knife adapted to be shifted into and out of operative position, an edge-guide for directing work past said stitch-forming mechanism, edge-guide supporting

means providing for shifting said edge-guide into and out of operative position relatively to said knife, and means for releasably coupling said edge-guide and knife for simultaneous movement thereof out of operative position. 5

2. In a sewing machine, in combination, stitch-forming mechanism including a vertically reciprocating needle, trimmer mechanism including a horizontally vibratory knife adapted to be swung about its fulcrum-axis into and out of an operative position adjacent to said needle, an edge-guide for directing work past said stitch-forming mechanism, and releasable coupling means connecting said knife and edge-guide for simultaneous movement out of operative position, said coupling means providing for operative work-trimming movements of said knife in a stationary operative position of said edge-guide. 10 15

3. In a sewing machine, in combination, stitch-forming mechanism including a vertically reciprocating needle, trimmer mechanism including a horizontally vibratory knife adapted to be swung about its fulcrum-axis into and out of operative position, and edge-guide for 20 25 directing work past said stitch-forming mechanism, edge-guide supporting means providing for swinging said edge-guide into and out of operative position about a pivotal axis substantially coincident with the fulcrum-axis of said knife, and a releasable coupling connecting said knife and edge-guide.

4. In a sewing machine, in combination, stitch-forming mechanism, trimmer mechanism including a vibratory knife adapted to be swung about a fulcrum-axis into and out of operative position, an edge-guide for directing work past said stitch-forming mechanism, and supporting means providing for swinging said edge-guide relatively to said knife about a pivotal axis substantially coincident with the fulcrum-axis of 30 35 40 said knife. 45

5. In a sewing machine, in combination, stitch-forming mechanism including a vertically reciprocating needle, a horizontally vibratory trimmer-knife carrier, a trimmer-knife actuating lever pivotally supporting said carrier for swinging movements into and out of operative position, a releasable connection between said carrier and lever, an edge-guide, a bracket pivotally supporting said edge-guide for swinging movements relatively to said carrier, and a releasable coupling connecting said edge-guide and knife-carrier. 50 55
